ABSTRACT: A safety closure for containers subjected to high internal pressures and of particular use for the isostatic method of shaping pulverulent materials. The closure plug, having an enlarged central recess, fits into the container and by means of cams on the closure plug and tappets on the container, a bayonet type connection is provided, the container wall at the upper end being extended outwardly to provide a space to accommodate the joint parts. The lower end of the closure plug which fits inside of the container is provided with a plurality of sealing rings, the lowermost of which is of elastomeric material, which is pressure responsive for sealing contact with the container walls. Fluid activated means is provided for vertically actuating the cover plug with respect to the container and power means is employed for rotating the cover plug to lock and unlock it to the container.

CLOSURE DEVICE FOR CONTAINERS SUBJECTED TO HIGH INTERNAL PRESSURES

BACKGROUND OF THE INVENTION

The fact that pressing methods carried out always more isostatically, in which the bodies pressed out of a pulverulent starting material are uniformly compressed on all sides in a pressure chamber under high pressure, requires the use of well sealed receptacles, in whose pressure chamber a fluid is brought to the required applied pressure. In this connection, it is understood in the following by fluid quite generally the pressure producing medium may be a liquid or a gas.

From the isostatic pressure technique, high speed closures are known, whose locking or sealing portion is constructed as bayonet-closure, so that a plurality of interrupted threads disposed on its periphery, enters upon locking into engagement with a likewise interrupted thread member in the container wall.

High speed closures are known in which force locking is produced by a bolt extending through a bore which leads through the container and the threaded plug or stopper.

Then there are known also high speed closures which have semicircular spirally disposed recesses on the vessel as well as on the closure, and in which then for the production of the force locking a spiral or helical spring is introduced.

The disadvantages of the closure mentioned first lie therein, that on account of the uniform distribution of the load a very accurate working and fitting is necessary. The first course or pitch of the screw thread seen from the pressure chamber must receive the greatest load, accordingly approximately 40 percent. With the second closure mentioned, the closure bolt is strained to shearing. With the third closure, the danger exists that in higher pressure areas the spiral or helical spring introduced is deformed and accordingly renders impossible a release of the closure.

With a known hydraulically actuated safety closure for high pressure steam sterilizers, the cover is pressed by means of a knee-lever device under influence of hydraulic forces on the rim of the vessel, whereby in the rim a packing is compressed by the cover or lid (German laid out specification No. 1,199,075). The pressures which may be held in such vessel are limited in height by means of the knee-lever arrangement and by the fact that the packing lies in the force locking. Furthermore upon failure of the hydraulic system, the force locking is no longer effective.

With a further known pressure container, the upper rim flange of this container is equipped with so-called tappets which are engaged in a bayonet lock manner by corresponding cams on the cover (German laid out specification No. 1,231,507). For the release of the cover, the latter is rotated for a half tappet cam division and then lifted upwardly, whereby the cams slide through the intermediary spaces between the tappets. The packing is set in a groove in the rim of the container. In this way indeed the packing is no longer in the flux of force of the closure, and it must, however, be necessary to insert quite a complicated construction involving a spring, in order to produce the required pressure of the packing or sealing ring. A sealing ring acting in this manner is not equal to the required high pressures.

SUMMARY OF THE INVENTION

With the safety closure for containers according to the invention, the disadvantages of the known devices are overcome because the receptacle inclusive of its internal space has in the area of the closure an increase in diameter. In the internal space on the upper end, tappets project in, forming one part with the inner wall of the receptacle, which may engage the closure stopper by means of correspondingly disposed cams, in the manner of a bayonet lock. The sealed closure plug at the point of the increase in diameter of the inner chamber is set back to provide an inward shoulder and from there extends for an interval downwardly into the internal chamber, so that a cylindrical chamber is formed, which receives the packing. In

this manner, the closure after application of the pressure in the container may be slid slightly axially, so that the plane surfaces of the tappets and the cams are connected in force lock and accordingly there results a subdivision between the force locking and the sealing functions.

The high speed closure according to the invention is particularly simple in its construction and is to be regarded in connection with the entire manipulation device as a safety closure. Upon its production, an increased dimensional accuracy is necessary solely for the tappets and cams. These advantages count as compared with known high speed closures in increased measure with larger closure diameters. A further advantage is imparted because even with high station times a secure locking is attained. Finally, the new closure can be produced at a very favorable cost.

The tappet and cam connection may in this embodiment receive pressures up to 10,000 kp/cm² at temperatures up to 250°C. The packing or seal is frontally subjected to the internal pressure of the vessel, and the sealing effect increases with increasing internal pressure. The closure is particularly adapted to an automatic actuation, because for the sealing and locking of the container no expenditure of force and time is required.

According to a further object of the invention, there is secured on the shoulder of the closure plug an elastic supporting ring made of a metal of high resistance, on which are disposed several plastic deformable sealing rings, to which a sealing ring is attached made of an elastomeric material, extending downwardly to the lower end of the closure plug. This seal or packing has been found particularly adapted to the high pressures. The plastic deformable sealing rings form an intermediary member between the sealing and the force transferring functions. The assembly is received with pressure by means of the elastic supporting ring which is of metal of high resistance and is disposed on the shoulder of the closure plug or stopper.

In order to lock the entire sealing device in the desired position, in accordance with the invention it is further provided that on the bottom surface of the closure plug, a ring is secured with a rim flange directed upwardly, whereby the rim flange projects into a groove or channel of the sealing ring made of elastomeric material and locks and pretensions the sealing ring.

For the simple and purposeful manipulation of the safety closure, in accordance with the invention, a fluid actuated lifting or hoisting cylinder is provided fixed on a retractable arm for raising and lowering the closure plug. With larger units, the lifting cylinder may also be mounted on a slideable carriage. After the goods to be compressed have been filled into an elastic mold and hydraulic fluid has been introduced into the receptacle, the closure fixed on the arm is swung over the opening of the receptacle and hydraulically lowered. After being lowered, and indeed at the same time with hydraulic force, the closure plug is rotated a half tappet and cam portion, the hydraulic system is released and the receptacle is accordingly securely closed, or sealed.

As was found further, the closure plug may have a centrally larger recess, and this has the advantage that the work space of the receptacle is enlarged up to 40 percent. Furthermore, there is attained thereby a more favorable course of the flow of force. Finally, in accordance with the invention, a bearing ring made out of a self lubricating material may be provided on the inner surface of the conical expansion or enlargement of the receptacle wall.

BRIEF DESCRIPTION OF THE DRAWINGS

FIG. 1 is a vertical section of a receptacle and plug according to the invention;

FIG. 2 is a top perspective view of the closure plug with the manipulating device, the plug being shown lifted and swung laterally; and

FIG. 3 is an enlarged fragmentary sectional view of the receptacle and closure plug showing in detail the tappet and cam lock and packings.

DESCRIPTION OF PREFERRED EMBODIMENT OF THE INVENTION

The sectional drawing according to FIG. 1 shows a receptacle 2, in which a plug 1 is inserted and locked. The closure plug 1 has a central elongate recess or chamber 3, which at the upper end has a central bore 4 of smaller diameter for the ventilation or pressure release. By means of the recess 3, the work space of the receptacle is enlarged up to 40 percent. Furthermore, there is attained thereby a more favorable course of the flow force. The upper part of the closure plug 1 carries a conical expansion or enlargement 5 and an upper attachment flange 6. Formed on the peripheral surface of the plug 1 is an annular row of cams 7, which have at the top a flat or smooth plane surface 8. The plug consists of steel and is forged out of one piece of blank material.

The receptacle 2 is likewise of steel, and forms with its cylindrical wall and its bottom wall 12 a pressure chamber 14. It is dimensioned for pressures up to 10,000 kp/cm² and more and is forged from a single block. In order to receive the closure plug the receptacle 2 is conically expanded and the upper part 11 thereof is cylindrical. In the inner wall of the cylindrical part 11 are seated an annular row of tappets 13, which cooperate with the cams 7 in establishing a bayonet closure. The construction of the inner wall of the part 11 of the receptacle, the wall of the closure plug 1 as well as the tappets 13 and cams 7 is such that the tappets 13 lie with their lower flat surfaces on the flat surfaces 8 of the cams 7 and in addition that there remains a slight gap between the parts on the closure plug 1 and the parts on the receptacle 2. At the lower end and on the outside of the closure plug 1 is a shouldered recess 9 for receiving a packing 10.

The manipulating installation of the device is shown in FIG. 2. The receptacle 2 is inserted in a base or floor 19, of which FIG. 2 shows a fragment, and in which appear the upper cylindrical portion and the tappets 13. On the floor 19 is fixed a post 20, on which an arm 21 is pivotally mounted. The arm 21 carries a hydraulic cylinder 22, in which moves a piston (not shown) on whose piston rod is suspended the closure plug 1. The closure plug is suitably connected through a spacer 24 with the hydraulic piston. The entire installation is manipulated hydraulically, for which purpose a series of pipe conduits 23 are provided. Above the closure plug 1 is disposed a gear segment or section 25. When in lowered position the plug 1 is rotated for a half tappet and cam section by a gear (not shown) engaging the gear segment 25. A guide and stop member 26 fixes the rotational movement of the locking and unlocking operation.

FIG. 3 shows on a larger scale the tappet and cam device and the packing. On the shoulder 9 of the closure plug 1 lies an elastic supporting ring 35 made of a metal of high resistance. It is carried out in such manner, that it is fitted with minimum play in the existing walls. From top to bottom there lie on this packing or sealing ring 35, two supporting rings 36 made of a plastic deformable material. Below the rings 36 is a packing 37 of elastomeric material.

The pressure in the interior space of the receptacle acts both on the closure plug 1 itself as well as on the seal or packing. The force taking effect on the closure plug 1 is absorbed in force locking through cams 7 and tappets 13 by the wall of the receptacle. In this flow of force lies no packing or seal. The packing or seal itself is subject at the same time to the internal pressure of the receptacle, which supports the packing 37 formed of elastomeric material against the two rings 36. The wedge shaped part of the elastomeric material 37 is pressed by means of liquid pressure with its lips against the inner wall of the receptacle and the outer wall of the plug

corresponding to the particular operational pressure.

The sealing rings are retained in place upon insertion and removal of the closure plug 1 by means of screws 39 which secure a ring 38 to the bottom face of the closure plug 1, said ring having an upwardly directed nose 40 projecting into a wedge shaped notch of the sealing ring 37.

A bearing ring 31 of a self lubricating material is provided on the inner surface of the conical enlargement of the receptacle wall.

10 A ventilation or pressure release bore 41 leads from the pressure chamber 14 to the outside to a screw coupled part 43, to which is connected a ventilation or pressure release pipe 42 by means of a pressure member 44 metallically sealed to the receptacle 2.

15 I claim:

1. A safety closure for cylindrical containers subjected to high internal pressures comprising:

a cylindrical container closed at its lower end and open at its upper end and having a pressure chamber;

20 a cylindrical enlargement at the upper portion of said container;

a circular row of inwardly projecting rigid tappets on the inner wall of said enlargement on the upper portion thereof;

25 a cylindrical closure plug having a flanged head to abut against the upper end of said enlargement;

a tubular extension on said head to project inside of said container for engagement at the lower end thereof with the walls of said pressure chamber;

30 said extension providing a chamber opening into said pressure chamber for enlarging the area of the latter;

a circular row of rigid cams on the outer wall of said closure plug at the lower end portion whereby upon turning of said plug said cams are disposed beneath said tappets respectively for releasably securing said closure plug to said container;

35 a shouldered cylindrical recess at the lower end of said closure plug facing the wall of said pressure chamber; and packing means in said recess providing a seal between the lower end of said closure plug and said pressure chamber.

2. A safety closure for cylindrical containers as claimed in claim 1, in which said packing means comprises an elastic metallic supporting ring abutting the shoulder of said recess, deformable plastic sealing rings adjacent said metallic supporting ring, and an elastomeric sealing ring disposed below said plastic rings.

3. A safety closure for cylindrical containers as claimed in claim 2, in which said elastomeric sealing ring has a wedge-shaped notch, a ring secured to the bottom end of said closure plug, and an upwardly directed nose on said ring projecting into said wedge-shaped notch.

4. A safety closure for cylindrical containers as claimed in claim 1, comprising a supporting ring of self-lubricating material on the inner surface of said cylindrical enlargement for engagement by said cams.

5. A safety closure for cylindrical containers as claimed in claim 1, comprising a base aperture to receive said container, an upright support on said base, an arm pivoted to said support for horizontal swinging movements, a lifting device carried by said arm and including a fluid operated piston attachable to said closure plug for lowering and lifting same, and means for turning said device for locking and unlocking said closure plug relative to said container.

6. A safety closure for cylindrical containers as claimed in claim 1, comprising a base aperture to receive said container, a slideable carriage on said base, a lifting device on said carriage including a fluid-operated piston attachable to said closure plug for lowering and lifting same, and means for turning said device for locking and unlocking said closure plug relative to said container.
